[57] **CLAIM**

The ornamental design for a lighting fixture, as shown and
described.

DESCRIPTION

FIG. 1 is a front elevational view embodying our new design
for a lighting fixture;

FIG. 2 is a rear elevational view thereof;

FIG. 3 is a side elevational view thereof;

FIG. 4 is a top plan view thereof; and,

FIG. 5 is a bottom plan view thereof.

The light bulbs are shown in broken lines for illustrative
purposes only and form no part of the claimed design.
